PAPERMAKING MACHINE

Drexel V. Smith and George W. Miles,
Mobile, Ala.

Application February 21, 1947, Serial No. 729,908

8 Claims. (Cl. 92—44)

1

This present invention relates to improvements in paper making machines and more particularly to a slice construction for controlling the output of the head box of such a machine.

The principal object of the invention is to provide a slice mechanism adjustable to readily obtain the maximum or minimum drainage at desired points on the Fourdrinier belt of a paper making machine. This adjustability is essential in making any and all weights and grades of paper and board at any speed.

To make some grades of paper, a highly refined pulp must be used and the maximum drainage time on the Fourdrinier must be allowed as such pulp drains slowly. Such maximum drainage time is not necessary when making paper from a pulp only very little refined and thus draining too rapidly in contrast to the highly refined pulp.

Another object of the invention is to provide a slice mechanism characterized and including a bottom slice controlling the drainage.

A further object is to provide a slice mechanism of simple and low cost construction and capable of adjustment while the machine is in operation. This feature eliminates shut downs of the head box of the machine, and this contributes substantially to a lowering of the cost of production.

Still another object of the invention is to provide a stand or bracket for mounting the slice mechanism and located rearwardly of the latter and also serving as a cat-walk for the operator while adjusting the slice. The cat-walk is so located that the operator adjusting the slice may maintain his upright position and, looking forwardly, observe the results of his adjustments.

With these and other objects in view which will become apparent as the invention is fully understood, the same resides in the novelty of construction, combination and arrangement of elements described hereinafter in detail and distinctly claimed in the subjoined claims.

The description should be read in connection with the accompanying drawings forming a part of the application and illustrating the practical application of the principles of our invention and wherein:

Fig. 1 is a side elevation partly in section of the preferred embodiment of our invention;

Fig. 2 is a front end view;

Fig. 3 is a longitudinal sectional elevation;

Fig. 4 is an enlarged longitudinal vertical detail section;

2

Fig. 5 is another longitudinal detail section taken on a plane parallel to that of Fig. 4;

Fig. 6 is an enlarged detail top plan view;
Fig. 7 is an enlarged detail front view.

In the drawings, in which like reference characters designate like or similar parts throughout the several views—

Figs. 1 and 3 show a fragment of a conventional Fourdrinier wire belt 10, trained over breast roll 11, and receiving paper stock from a head box 12, which has its side surfaces tapering inwardly in the direction of its lower end inlet (not shown) as indicated in dotted lines in Fig. 2.

The upper end of the head box 12, is curved forwardly and forms the forwardly arched portion 13 of the back wall. The inner concave surface 13a of the portion 13 will impart to the pulp an initial rolling action. By causing the pulp to roll immediately prior to its discharge, an interfibering action takes place which makes it possible to deposit a sheet of uniform texture on the Fourdrinier 10, described.

The pulp is discharged over the forwardly declining bottom 12b, of and through a horizontal head box outlet 14, which at its rear end is connected to or integral with the horizontal extension 13b, of the arched outlet portion 13, of head box 12. Extension 13b forms a shortened top wall of outlet 14.

Head box 12, is fixedly supported on a frame or pedestal 15, having at its lower end laterally and horizontally extending flanges 15a, secured by bolts 15b, to the rearwardly extending horizontal flange 16a, of a drain pipe 16. The flange 16a, rests upon the machine room floor 17.

The outlet spout 14, and curved head box portion 13 extend the full width of the Fourdrinier belt 10. The outlet spout 14 is a rectangular box open at its rear and front ends and has the aforementioned forwardly declining bottom 12b, which terminates rearwardly of the forward end of the top wall 13b (see Fig. 3). The vertical side walls of the outlet 14, have extensions 14a, projecting substantially forwardly of the top and bottom walls 13b, 12b, respectively.

To close the bottom opening which extends between the lower ends of the vertical outlet sides and extensions 14a, a bottom slice 14b, is provided (Fig. 3) which takes the form of a plate of a width equal to the outer width of the outlet 14 and carrying near its transverse ends and on its top side, T-shaped ribs 14c (Fig. 2). The same fit into corresponding T-grooves 14d, each formed in the lower edge portions of and opening through the lower edges of the head box out-

let sides 14a. The bottom slice 14b tapers on top forwardly to a thin edge (see Figs. 2 and 3), and has its rear portion slideable in a recess 14e, of bottom outlet wall 12b. This recess 14e, is open at the bottom and is located above the pedestal or frame 15.

Turning to Fig. 3, it will be noted that upon the lower side of the bottom slice 14b, are formed a desired plurality of spaced racks 14f, each in mesh with one of an equal plurality of gears 14g. All of the latter are fixed upon a transverse horizontal shaft 14h, journaled in the top part of pedestal 15.

The frame or pedestal 15, is also provided with recesses 14i, each to accommodate a gear 14g, and opening through the top surface of the stand. The ends of shaft 14h, project beyond the ends of pedestal 15, as shown in Fig. 2, and are squared for the attachment of a wrench whereby the bottom slice 14b may be moved to the desired position. Bottom slice 14b is adjustable to a position in which its front end is a predetermined distance, say two inches forward of the axis of breast roll 11, and to a position in which the same end is a predetermined distance, say two inches rearwardly of such axis.

A cam shaft 15x, has its cylindrical end portions journaled in the transverse ends of the forwardly projecting portion of pedestal 15, and projecting beyond these ends. The intermediate portion of this shaft 15x, forms an eccentric cam 15y, movable in a recess 15c, formed in the top portion of the pedestal 15, and opening through the top surface thereof. When the shaft 15x is turned counterclockwise from a certain position, its cam will grip the under side of the bottom slice 14b, and hold the same in position.

Referring to Figs. 1 and 2, it will be seen that the cylindrical end parts of shaft 15x, carry each an arm 15d, having an opening in its free end. An eye bolt 15e, is pivoted to the frame by means of its eye and a pin 15f, inserted therein and extending from the frame. The bolt 15e, is disposed through the opening in arm 15d, and may be pulled through such opening by the turn of a nut 15g, with the result that cam 15y, engages the underside of the bottom slice 14b, as indicated in Fig. 3.

Upon the top wall of head box outlet 14, and partly supported by the adjacent pulp-rolling arched portion 13, is fixedly mounted a bearing and guide-providing housing 18, which extends the full width of said outlet 14. Housing 18, provides horizontal guideways at its sides adjacent the shortened top wall 13b, of outlet 14 (see Figs. 3, 4 and 5), for a plate 20. This plate 20 carries at its front end the horizontally adjustable stand or support 19, for the vertically adjustable slice 33, 34 which will now be dealt with.

A pair of guide rods 21, are secured at their front ends to said vertical slice stand 19, and guided for horizontal movement in the housing 18, at the sides thereof. The rear portion of each guide rod 21, is provided on its top side with teeth 22, forming a rack and adapted for meshing with a gear 23.

The gears 23, one for each rack 22, are fixed upon transverse horizontal shaft 24, journaled in housing 18, and carrying on either end projecting beyond the sides of the housing, a hand wheel 25.

Turning to Figs. 2 and 3, it is seen that a transversely disposed horizontal cam shaft 26,

has cylindrical ends 26a, each journaled in and extending beyond the sides of the housing 18, adjacent the bottom thereof. The intermediate portion of shaft 26, forms an eccentric cam adapted to engage the subjacent stand-carrying plate 20, and hold the same in a desired position to which rotation of hand wheel 25, has moved it. Shaft 26, has upon either end projecting beyond the sides of the housing 18, an arm 30, which has an opening in its end for the passage of an eye bolt 29. This eye bolt 29 is pivoted by its eye upon a pin 31 projecting from the vertical side of the housing 18, and has upon the other end threads engaged by a nut 32, the turning of which will force the cam 26, against the top side of plate 20. As will be understood, plate 20 provides to the extent desired, a cover for the open top of the outlet 14, and in advance of the shortened top wall 13b thereof and between the side wall extensions 14a.

In the top of the slice stand 19, is journaled a shaft 32a, extending transversely and horizontally of the outlet 14, and beyond the opposite ends of said stand 19, as shown in Fig. 2. The end portions of the shaft 32a, projecting beyond the slice stand 19, carry each a hand wheel 32b. The intermediate portion of shaft 32a, between the journals is provided with a pair of spaced worms 32c, each of which meshes with a worm gear 32d. The worm gears 32d, rest upon the upper edges of a pair of spaced vertical walls 37, forming part of the stand 19. The spaced stand walls 37, have pairs of aligned transverse holes at opposite sides for rods 21, the forward ends 35 of which are fastened in stand 19.

Each worm gear 32d, carries on its top side a coaxial screw 32e, each engaging a nut 32f. Each nut 32f, is the lateral end of an adjustable frame including a horizontal top bar 32g, and a downwardly extending arm 32h, which latter is secured to the upper part of a slice carrying plate structure 34. This slice-carrying plate 34, is disposed between the vertical stand walls 37, and is guided thereby during its vertical adjustment with frame 32g, 32f, etc., by the rotation of hand wheels 32b.

As shown in Fig. 2, the vertical slice-carrying plate 34, is substantially coextensive in width with the front opening of the outlet 14, and is, as stated, slideable in stand 19. This plate 34 is provided at its lower edge with a coextensive horizontal slot 34a for the vertically adjustable top slice 33. The plate 34, is further provided with a plurality of laterally spaced vertical holes 34b, each for a rod 35, which is welded or otherwise connected (36) at its lower end to the upper edge of the flexible top slice strip 33.

The upper end portion 35a, of each rod 35, is threaded for engagement in a hand nut 35b, which, as shown in Fig. 5, has a hub part journaled in an opening in the top bar 32g, and a flange at the lower end. The top slice 33, serves the purpose of maintaining the proper thickness of the paper sheet on the Fourdrinier 10, and of levelling the sheet across said Fourdrinier wire.

The pulp runs onto the Fourdrinier wire 10, before coming in contact with the vertical top slice 33, and is carried under said slice 33, thereby eliminating the spurt of pulp during the latter's discharge onto the wire 10. Thus, the pulp is more easily controlled and given a better formation.

The top slice 33, is horizontally adjustable, through movement of its stand 19, to predetermined extreme positions, one of which we shall

say is two inches rearwardly of the axis of the breast roll 11, and the other, say to a position ten inches forward of such axis. This horizontal adjustment of the top slice stand 19, the vertical adjustment of the slice-carrying frame 32g, 32f, 34, and for that matter, the vertical adjustment of top slice 33, per se (still to be described), can be made by an operator using the housing 18, as a cat-walk. This is a distinct advantage over the prior art in which the cat-walk for the operator is either forward of the slice or above the same. Such prior art arrangement compels the operator to stoop down or lie down while making adjustments and to raise his head to see the results of his adjustment or to stand upright while adjusting and looking backward over his shoulder to see results. In our construction, the operator may make adjustments in an upright position and see the results of such adjustments.

The top slice is vertically adjusted by rotation of one of the hand wheels 32b and hand nuts 35b.

Adverting again to the vertical slice carrying stand 19 of Figs. 2 and 3, it will be noted that its bottom carrying plate 20 is supported at its sides on lineally extending shoulders 40 of the extended side walls 14a of outlet 14. Also, inner surfaces of the side walls of housing 18 provide continuation grooves 41 in line with shoulders 40 and the shortened top wall 13b of outlet 14 has a recess 42 connecting said grooves 41 as indicated in Fig. 3. Thus, the rear end of plate 20 will be housed and supported as indicated in Fig. 3. Housing 18 above the recess 42 and adjacent its forward end, has the transverse recess 43 which accommodates the cam 26. Of course, guiding and sustaining of the rear end of plate 20 may be otherwise provided for.

While we have illustrated and described the improved paper making apparatus of our invention in a more or less detailed manner, it will be understood, of course, that the invention is not to be regarded as limited to the particular arrangements illustrated and described but includes all changes and variations which do not constitute a departure from the spirit and scope of the invention and the appended claims.

We claim:

1. In a paper making machine comprising in combination a Fourdrinier belt, an upstanding paper pulp supplying headbox therefor and being of relatively great height as compared to width and thickness, said headbox including at its upper end a substantially horizontal pulp outlet spout having top, side and bottom walls; a horizontally movable bottom slice projectable beyond the outer end of said bottom wall, a subjacent pedestal supporting said spout, the top of said pedestal and the outer surface of said bottom spout wall providing a horizontal bottom-slice-receiving guide space closed at the sides but opening in the direction of travel of said belt and in a plane above the same, said bottom slice being slidable in the bottom guide space, actuating means for moving said bottom slice with respect to said belt, a housing carried by said outlet spout and substantially coextensive in width therewith, a vertically adjustable top slice movable toward and away from said belt, a horizontally adjustable stand therefor carried by said housing, and actuating means for each of said top slice and its stand.

2. In a paper making machine comprising in combination a Fourdrinier belt, an upstanding paper pulp supplying headbox therefor, said headbox including at its upper end a substantially

horizontal pulp outlet spout having top, side and bottom walls; a horizontally movable bottom slice projectable beyond the outer end of said bottom wall, a subjacent pedestal supporting said spout, the top of said pedestal and the outer surface of said bottom spout wall providing a horizontal bottom-slice-receiving guide space closed at the sides but opening in the direction of travel of said belt and in a plane above the same, said bottom slice being slidable in the bottom guide space, a housing carried by said outlet spout and substantially coextensive in width therewith, a vertically adjustable top slice movable toward and away from said belt, a horizontally adjustable stand therefor carried by said housing, and actuating means for each of said top slice and its stand.

3. In the combination set forth in claim 2, said horizontally adjustable top slice stand having a rearward extension within said housing, and locking means engaging said stand extension and carried by said housing, said locking means being operable from the top of said housing.

4. In a paper making machine comprising in combination a Fourdrinier belt, a paper pulp supplying headbox therefor and including a pulp outlet spout, a bottom slice movable outwardly as an extension of the bottom of said spout, a pedestal supporting said spout, said pedestal top and the bottom of said spout providing a guide recess for said bottom slice, said bottom slice being slidable in said recess, means for moving said bottom slice with respect to said belt, a housing carried by said spout and in part by said headbox, said housing being coextensive in width with said spout and headbox, a top slice stand movably carried by said housing for limited travel in the direction of movement of said belt, and a top slice vertically adjustably carried by said top slice support.

5. A paper making machine comprising in combination a Fourdrinier belt, a head box for delivering paper pulp material to said belt, an outlet delivery spout extending horizontally from the head box, said spout including bottom, top and side walls, a pedestal supporting the head box and delivery spout, the bottom wall of the spout being tapered toward its forward edge, a horizontally movable bottom slice mounted in a recess formed between the top of the pedestal and the bottom of the spout, the bottom slice being movable outwardly past the bottom wall of the spout and guided in said recess, a bearing and guide-providing housing coextensive with the top wall of the outlet spout, a horizontally movable vertical slice stand mounted adjacent said housing, movable guide and supporting rods extending into the housing, a vertically adjustable slice plate mounted in said vertical slice stand and means carried by the vertical slice stand for vertically adjusting the slice plate to vary the thickness of pulp fed to the Fourdrinier belt.

6. The combination recited in claim 5 including, a horizontal rod having gears thereon mounted in a recess in the top of the pedestal, the rod extending outwardly past each side of the pedestal, the horizontally movable bottom slice having racks on its under side engageable by the gears to horizontally move the bottom slice and thereby control the point at which the pulp is fed to the Fourdrinier belt.

7. In the combination recited in claim 5, said pedestal having a cam mounted in a recess within the upper portion of the pedestal and operable

to engage the bottom slice and hold the same in fixed position.

8. A paper making machine comprising in combination a Fourdrinier belt, a head box for delivering paper pulp material to said belt, an outlet delivery spout extending horizontally from the head box, said spout including bottom, top and side walls, a pedestal supporting the head box and delivery spout, the bottom wall of the spout being tapered toward its forward edge, a horizontally movable bottom slice mounted in a recess formed between the top of the pedestal and the bottom of the spout, the bottom slice being movable outwardly past the bottom wall of the spout and guided in said recess, a bearing and guide-providing housing coextensive with the top wall of the outlet spout, a horizontally movable vertical slice stand mounted adjacent said housing, movable guide rods extending into the housing, a vertically adjustable slice plate mounted in said housing and means carried by the vertical slice stand for vertically adjusting the slice plate to vary the thickness of pulp fed to the Fourdrinier belt, a cross shaft mounted in said housing, gears mounted on said cross shaft, racks on the vertical slice stand guide rods

engageable by said gears to horizontally move the housing and its slice plate, said housing including a plate fitting within a recess formed within the top wall of the spout, and a cam shaft mounted in a recess in the housing and operable to lock the housing in horizontally adjusted position.
